UNITED STATES PATENT OFFICE.

ALLEN C. HIGGINBOTHAM, OF CHARLESTON, WEST VIRGINIA.

BOLTING-CLOTH CLEANER.

1,142,096.

Specification of Letters Patent. Patented June 8, 1915.

Application filed May 26, 1914. Serial No. 841,144.

To all whom it may concern:

Be it known that I, ALLEN C. HIGGINBOTHAM, a citizen of the United States, residing at Charleston, in the county of Kanawha and State of West Virginia, have invented new and useful Improvements in Bolting-Cloth Cleaners, of which the following is a specification.

This invention relates to improvements in devices for automatically cleaning the cloth of flour bolting sieves and the object of the invention is to provide improved means whereby the movement of the brushes will be automatically reversed and the operation will be positive in either direction of movement.

A further object of the invention is to so arrange and construct the parts of the operating mechanism that the brushes will be compelled to move a full stroke in either direction before starting upon the reverse movement.

Another object of the invention is to provide improved brush operating means of this class in which the rack bar, the traveler, the dog and the reversing devices are arranged on the outer sides of the sieves where they are entirely out of the way of the flour and material in the sieves, are not liable to become clogged and rendered inoperative thereby and moreover are exposed to view so that the attendant can assure himself from time to time that the cleaning brushes are in operation.

Another object of the invention is to provide means for controlling the speed of operation of the brush actuating devices.

Another object of the invention is to effect improvements in the construction of the means for carrying the brushes and by means of which the brushes are rendered independent of one another and are adapted to automatically adjust themselves so as under all conditions to bear closely against the under side of the bolting cloth and thereby increase the cleaning efficiency of the brushes.

With the above and other objects in view the invention consists in the construction, combination and arrangement of devices hereinafter described and claimed.

In the accompanying drawings:—Figure 1 is a top plan view of one of the sieves and provided with my improved bolting cloth cleaners, the bolting cloth being partly removed to disclose the construction of the

cleaners. Fig. 2 is a detail vertical sectional view on a larger scale, on the plane indicated by the line *a—a* of Fig. 1. Fig. 3 is a detail vertical sectional view on the plane indicated by the line *b—b* of Fig. 1. Fig. 4 is a detail elevation of one of the brush carriers and indicating the brushes thereon, the operating rod being indicated in section. Fig. 5 is a plan of the same on a larger scale than that of Fig. 1 and corresponding with the scale of Fig. 4. Fig. 6 is a detail vertical sectional view on the plane indicated by the line *c—c* of Fig. 4.

The screen frame 1 may be of the usual or any preferred construction and is here shown as gyratory and operated by the means usually employed. Each sieve 2, of which there may be any suitable number, according to the capacity of the bolter, is formed in sections 3. A brush carrier 4 is arranged for operation in each sieve section and carries a pair of bolting cloth cleaning brushes 5. The bolting cloth cleaning device is indicated at 6. The brush carriers of each sieve are connected to an operating rod 7 which extends through an opening in one side of the sieve, projects at one end from the said side of the sieve and is provided at its exposed projecting end, exteriorly of the sieve, with a substantially U-shaped traveler 8.

A plate 9 is arranged exteriorly of the sieve and is secured on the side thereof through which the operating rod 7 extends and the said plate is provided with a rectangular opening 10 through which said rod also extends. The rod is engaged on opposite sides by a pair of blocks 11—12 the former fixed and the latter movable. The said blocks are arranged in the opening 10 and the movable blocks 12 are engaged on its outer side by a spring 13. An adjusting screw 14 operates in a threaded opening in a lug 15 with which the plate 9 is provided. Said screw bears at its inner end on the outer end of the spring 13 and is provided at its outer end with a hand wheel 16 whereby it may be readily turned. The spring operates in an opening 17 in the plate. By appropriately adjusting the screw the spring may be caused to bear with any desired tension against the block 12 so as to create any desired degree of friction between the operating rod 7 and the blocks 11 and 12 which engage opposite sides thereof and thereby control the speed

of movement of the operating rod and the brushes connected thereto.

A rack bar 18 has one end attached as at 19 to the plate 9, extends outwardly from 5 and is arranged exteriorly of the sieve and is provided at its end, on its upper side, with reversely arranged inclined upwardly converging reversing cams 20—21. The rack teeth 27 are on the upper side of the rack 10 bar and are provided each with inclined upwardly converging sides. The rack teeth being triangular in form the vertical arms of the traveler 8 are arranged on opposite sides of the rack bar so that the latter serves 15 to guide the traveler and between the upper ends of the arms of the traveler is a dog 23 which is pivotally mounted at its center as at 24. The dog has oppositely extending arms 25—26 which are arranged at an angle 20 to each other and are adapted to engage opposite sides of the teeth of the rack bar successively according as one arm of the dog or the other is so engaged. A spring 27 is also provided which bears on the central 25 portion of the dog and holds it when either of its arms is in engaged position and yet readily permits the dog to be readily turned as to reverse it.

Motion being imparted to the sieves in the 30 operation of the bolter one arm of each dog will engage the rack bar of each sieve and impart motion to the brushes in the same direction as that followed by the sieves. When the brushes have moved to the full 35 extent in one direction the disengaged arm of the dog of each sieve will be engaged by one of the reversing cams so as to turn the dog and cause the previously disengaged arm to be engaged with the rack bar and 40 the previously engaged arm of the dog to be disengaged therefrom and hence the brushes will be caused to move in the opposite direction, the reversing cams serving to reverse the position of the dogs at the ends of 45 the path of movement of the travelers as will be understood.

It will be observed that all of the brush actuating devices are arranged exteriorly of the sieves, out of the way of the flour and 50 material in the sieve and hence are not liable to be clogged or the operation thereof rendered uncertain. Moreover the brush actuating devices, being thus exteriorly arranged, may be readily inspected to enable 55 the attendant to ascertain positively that the brushes are in operation.

Each brush carrier 4 is a cross bar having a central opening through which the 60 rod 7 extends. On the center of each brush carrier, on one side thereof is a yoke 28 which is bent as shown, has its central portion provided with an opening through 65 which the rod 7 extends and has its ends attached to the carrier as at 29. A sleeve 30 is arranged on the rod, between the car-

rier and the yoke and is secured to the rod as by means of a suitable set screw thereby securing the carrier firmly to the rod for movement therewith and yet enabling the carrier to be detached from or adjusted on 70 the rod as will be required. The yoke has its central portion formed with oppositely extending guide arms 31 which are spaced from the carrier.

Each carrier is provided with a pair of 75 brushes 32 the backs 33 of which are centrally pivoted as at 34 near the ends of the carrier the pivots 34, which are here shown as screws, being arranged for movement in vertical slots 35 with which the carrier is 80 provided. Bracket arms 36 are also secured on the carrier near the ends thereof and extend under the same and also under the brushes. Springs 37 are secured near their centers as at 38 to the brackets and 85 are arranged with their ends bearing under the brush heads, the said springs exerting their tension to raise the brushes so as to keep them always in engagement with the under side of the bolting cloth and the 90 pivots 34 of the brushes adapting them to accommodate themselves to the bolting cloth so as to keep the brushes always in contact therewith and insure the cleaning 95 of the cloth.

While I have herein shown and described a preferred form of my invention I would have it understood that changes may be made in the form, proportion and construction of the several parts without departing 100 from the spirit of the invention and within the scope of the appended claims.

Having thus described my invention, I claim:

1. In combination with a sieve, cleaning 105 brushes mounted for movement therein, a rack bar movable with and carried by the sieve, reversing devices at the ends of the rack bar, an operating rod for and movable with the brushes, a traveler on said rod and 110 guided by the rack bar, a reversible dog mounted on the traveler, coacting with the rack bar to actuate the brushes and reversed by the reversing devices to cause the brushes to move first in one direction and then in 115 the reverse direction.

2. In combination with a sieve, cleaning 120 brushes mounted therein, an operating rod for the brushes, means carried by and driven by the gyratory movement of the sieve to move the actuating rod and thereby move the brushes, and means to regulate the speed of the rod and brushes.

3. In combination with a sieve, cleaning 125 brushes mounted therein, an operating rod 130 for the brushes, means carried by the sieve to move the actuating rod and thereby move the brushes, and means to regulate the speed of the rod and brushes and comprising a friction device bearing against the rod and 135

means to vary the frictional tension of said device against the rod.

4. In combination with a sieve, cleaning brushes mounted therein, an operating rod connected to the brushes and extending through one side of the sieve, a carrier connected to said rod, a rack bar arranged exteriorly of the sieve and connected to said side thereof, reversing devices at the ends 10 of the rack bar, a traveler on the rod and attached thereto and a dog carried by said carrier and to engage the rack bar, said dog being reversed by the reversing devices.

5. In combination with a sieve, a brush ac-

tuating rod extending therethrough, a carrier attached to and movable with the rod, brushes pivotally connected to the carrier and arranged for vertical movement and springs carried by the carrier and exerting their tension to raise the brushes and yet 20 permit pivotal movement of the brushes.

In testimony whereof I affix my signature in presence of two witnesses.

ALLEN C. HIGGINBOTHAM.
